(57) **CLAIM**

The ornamental design for a cord winder, as shown and described.

DESCRIPTION

FIG. 1 is a lower front right perspective view of a cord winder, such as may be used with a communications headset, the broken line drawing of a clothing clip in the drawings herein is for illustrative purposes only and forms no part of the claimed design.

FIG. 2 is an upper rear left perspective view of the cord winder.

FIG. 3 is a front elevational view of the cord winder.

FIG. 4 is a rear elevational view of the cord winder.

FIG. 5 is a left side elevational view of the cord winder.

FIG. 6 is a right side elevational view of the cord winder.

FIG. 7 is a top plan view of the cord winder; and,

FIG. 8 is a bottom plan view of the cord winder.
